UNITED STATES PATENT OFFICE.

DAVID C. MARSHALL, OF NEWARK, NEW JERSEY.

ESCAPE APPARATUS FOR SUBMARINE BOATS.

1,173,726.

Specification of Letters Patent. Patented Feb. 29, 1916.

Application filed April 20, 1915. Serial No. 22,550.

To all whom it may concern:

Be it known that I, DAVID C. MARSHALL, a citizen of the United States, residing at Newark, in the county of Essex and State 5 of New Jersey, have invented certain new and useful Improvements in Escape Apparatus for Submarine Boats; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

The present invention relates, generally, to improvements in safety devices for submarine boats; and the invention has reference, more particularly, to improvements in 20 escape exit means for removing the members of the crew of a disabled and sunken submarine boat, which is itself unable to rise to the surface of the water, or be quickly raised to the surface of the water by outside aid.

The invention has for its principal object to provide a simple, compact and easily installed and carried apparatus for connection with submarine boats, which can be liberated 30 from the interior of the boat in the event of disaster overtaking the same, and which can be raised to the surface of the water independently of the boat so as to establish a communicating water-tight passage between the surface of the water and the interior of the boat, and through which the members of the crew may be raised, and thus liberated from confinement within the boat.

Another object of this invention is to provide in connection with this safety escape apparatus a tackle carrying float or buoy which, when liberated, will convey to the 40 surface lines or tackle for hauling up the safety escape apparatus from the sunken boat to the surface of the water, and which will at the same time serve to locate the vicinity of the disabled submarine boat by floating on the surface of the water above the same.

A further object of the invention is to provide a pressure resisting carrier or elevator member into which the members of the crew may enter, and in which they may be hoisted through the escape passage provided by the safety escape apparatus to the

surface of the water, without being subjected to the effects of the pressure of the water at the depth at which the disabled submarine boat lies. This carrier or elevator member being of such novel construction that it can readily be hauled up and down through said escape passage, without danger to the walls thereof and regardless of the water pressure on said walls, to and from the surface of the water and the sunken boat.

Other objects of the present invention, not at this time more particularly enumerated, will be clearly understood from the following detailed description of the same.

With the various objects of the present invention in view, the same consists, primarily, in the novel construction of safety escape apparatus for submarine boats hereinafter set forth; and the invention consists furthermore, in the novel arrangements and combinations of the various devices and parts, as well as in the details of the construction of the said parts, all of which will be more fully described in the following specification, and then finally embodied in the claims which are appended to and which form an essential part of the said specification.

The invention is clearly illustrated in the accompanying drawings, in which:—

Figure 1 is a vertical longitudinal section of the novel construction of escape apparatus as connected with the hull of a submarine boat, the same being made according to and embodying the principles of the present invention. Fig. 2 is a plan or top view of the closed casing or well in which the releasable portions of the safety escape apparatus are confined, the hatch or well cover thereof being shown in its normally closed position. Fig. 3 is a side elevation of a sunken submarine boat, showing the hatch or cover of the well or casing in open position, and the tackle carrying a float or buoy liberated from the well or casing so as to carry up a line from the boat, as well as to indicate its position or vicinity. Fig. 4 is a similar view but showing a rescue ship at the surface above the sunken submarine, and the escape apparatus raised from the latter and ready for use. Fig. 5 is an elevation or side view of a novel carrier or elevator member positioned in the passage of said escape apparatus as operated to carry a member of the submarine crew.

therethrough to the surface of the water. Fig. 6 is an end view of said novel carrier or elevator member. Fig. 7 is a detail section through the wall of the casing or well 5 and the deck of the submarine boat, and illustrating a water admission valve operable from within the submarine boat to admit water into said casing or well before the hatch or cover thereof is opened.

10 Similar characters of reference are employed in all of the hereinabove described views to indicate corresponding parts.

Referring now to said drawings, the reference-character 1 indicates the deck-portion 15 of the hull of a submarine boat 2. Built in connection with the said deck-portion 1 is a well or casing 3. The upper portion of said casing or well 3 preferably projects above the level of said deck-portion, while 20 its lower end projects downwardly through said deck-portion and partially into the interior of the boat. The lower or inner end of said casing or well 3 is closed by a permanent bottom partition or wall 4. Connected with said bottom partition or wall 4 is a tubular hatch-way 5, the upper end of which projects into said casing or well 3. The lower end of said tubular hatch-way 5 is normally closed by a hermetically sealed 30 door or hatch-plate 6 secured thereto by any suitable means and in any convenient manner. Telescoping over the upper end of said tubular hatch-way 5, which extends upwardly into said well or casing 3 and securely attached thereto by any suitable means, such as, for example the riveted clamp-band 7, is the lower end of a foldable or collapsible tubular body 8 the interior of which provides a safety escape or 40 exit passage from which water is excluded. A suitable length of said tubular body 8 is folded and piled up in a compact collapsed form within the interior of said well or casing 3; a suitable shelf, as 9, may be provided 45 for its proper support, and thus the said tubular body is normally stowed away when not in use, but in a manner which renders it quickly available for use in case of the sinking of the submarine boat. Passing through 50 the interior of said tubular body 8, and extending therethrough even when collapsed and normally stowed in the well or casing 3, is a light line or rope 10, the purpose of which will be subsequently explained. The 55 outer or free end 11 of said tubular-body 8 is normally sealed or closed in any suitable manner against the entrance of water therein when the same is hauled up to the surface, as will subsequently be described. To the 60 outer or free end 11 of said tubular body 8 is secured, in any suitable manner, one end of a stout hawser or cable 12, which is normally coiled up compactly so as to be stowed in said casing or well 3 above the folded 65 and stowed tubular body 8. Secured to the

opposite or free end of said hawser or cable 12 is a light line or rope 13, which is also normally coiled up compactly so as to be stowed in said casing or well 3 above the stowed collapsed tubular body 8. Secured 70 to the opposite or free end of said light line or rope 13 is a buoy 14 which is normally stowed away in said casing or well 3. The outer or upper end of said well or casing 3 is provided with a marginal coaming 15 75 which provides a seat portion 16 upon which is normally seated a gate or cover-member 17 which normally closes said casing or well 3 against the entrance of water therein, and the release of the buoy 14. A gasket 18 is 80 interposed between said seat portion 16 and said gate or cover-member 17 to render the same hermetically sealed and water tight. The means for supporting and operating said cover-member or gate 17 comprises, a 85 vertically mounted shaft 19, to the upper free end of which is secured a bracket member 20 the radiating arms 21 of which extend over and are riveted to said cover-member or gate 17 so as to support the same in 90 connection with said shaft 19. A suitably disposed bracket-bearing 22 provides means for rotatably supporting the upper end of said shaft 19. Mounted upon the lower end of said shaft 19 is an independently rotatable exteriorly threaded sleeve 23, which is mounted to screw up and down in a nut-piece 24 fixed in the deck-portion 1 of the submarine boat 2. As thus disposed the sleeve 23 projects downwardly into the interior of the submarine boat 2, and likewise the shaft 19 extends through said sleeve so that its lower end is disposed within the interior of the submarine boat 2. The upper end of said sleeve 23 abuts against a fixed collar 23' secured to said shaft 19, so that any longitudinal upward movement of said sleeve is likewise imparted to said shaft. The lower end of said sleeve is provided with a socketed collar 25 for the application 100 of a capstan bar 25' thereto for turning said sleeve 23, and in like manner the lower end of said shaft is provided with a socketed collar 26 for the same purpose. Of course, it will be apparent that any other mechanical means may be employed for turning said sleeve and said shaft, hence I do not wish to be limited to the use of such socketed collars and capstan bars.

The reference character 27 indicates a 120 latch member or clamp for engaging the opposite end of said cover-member or gate 17 to hold the same securely pressed down upon its seat in closed relation to said casing or well 3. The hub 28 of this latch member or clamp 27 is fixed upon the upper end of a vertically extending rotatable shaft 29. A suitably disposed bracket-bearing 30 provides means for rotatably supporting the upper end of said shaft 29. Mounted upon 125

the lower end of said shaft 29 is an independently rotatable exteriorly threaded sleeve 31, which is mounted to screw up and down in a nut-piece 32 fixed in the deck-portion 1 of said submarine boat 2. As thus disposed the sleeve 31 projects downwardly into the interior of the submarine boat 2, and likewise the shaft 29 extends through said sleeve so that its lower end is disposed within the interior of the submarine boat 2. The upper end of said sleeve 31 abuts against a fixed collar 31' secured to said shaft 29, so that any longitudinal upward movement of said sleeve 31 is likewise imparted to said shaft. The lower end of said sleeve is provided with a socketed collar 33 for the application of a capstan bar 25' thereto for turning said sleeve 31, and in like manner the lower end of said shaft 29 is provided with a socketed collar 34 for the same purpose. Of course, other mechanical means for turning respectively said sleeve 31 and shaft 29 may be provided, without departing from the scope of this invention.

25 The reference character 35 indicates an inlet pipe connected with and communicating with the interior of said casing or well 3, the outer end of the same being open to the admission of the sea water when the submarine boat is submerged. Said inlet pipe 35 is provided with a water admission or gate valve 36, the operating stem 37 of which is inclosed in a sleeve 38 which extends down through the deck-portion 1 of the submarine boat so that the handle 39 of the same is located within the interior of the boat, therefore rendering it possible to open said valve 36 from within the boat so as to admit water into the casing or well 3 when desired.

40 The reference character 40 indicates a suitable carrier or elevator-member, which is constructed to be drawn up and down through the tubular-body 8 when the escape apparatus is in use. The said carrier or elevator member 40 is adapted to carry the members of the crew of a sunken submarine, one at a time, through the tubular body 8 to the surface of the water. The said carrier or elevator member may be made in any desirable form or construction, and of any suitable material. As shown in the drawings the preferable construction is to make the carrier or elevator member in the form of a hollow cylindrical body of metallic construction, provided with an opening 41 giving entrance thereto, so that a member of the crew may enter the same and stand upright therein. The ends of said cylindrical body may be provided with conical heads 42, to the ends of which the draft-eyes or rings 43 are secured for the attachment of the hauling lines 44 and 45 thereto. The said heads 42 may be further provided with longitudinally extending ribs 46 on their exterior surface, so that the friction of the contact of said

heads with the inside of the walls of said tubular-body 8 is reduced to a minimum.

The manner of use and operation of said above described safety apparatus is briefly as follows: When the submarine boat 2 becomes disabled and sinks to the floor of the sea, the crew confined therein open the cover-member or gate 17 of the casing or well 3. To accomplish this the sleeves 23 and 31 are turned to elevate the same in their respective nut pieces, which operation moves longitudinally upward the respective shafts 19 and 29. The bracket member 20 and the hub 28 fixed on the respective shafts 19 and 29 may each be provided with lift-fingers 75 47 which extend under the protruding marginal edges of said cover-member or gate 17, so that as the respective shafts 19 and 29 move upward a slight lifting movement is imparted to said cover-member or gate 17 80 to raise the same off of its seat 16. If the submarine boat 2 lies in water of a depth sufficient to create a pressure rendering difficult the raising of the cover-member or gate in the above described manner, the valve 36 90 may be opened to admit sea water into said casing or well 3 and beneath said cover-member or gate 17 thus equalizing the pressure thereon, and rendering easy of accomplishment the raising of the same from its seat. After said cover-member or gate has thus been raised from its seat, the latch-member 27 is turned away from holding engagement with the same by rotating said shaft 29, and then by rotating said shaft 19 95 100 in a similar manner the said cover-member or gate 17 is rotated edgewise or horizontally through the water and away from the mouth of said casing or well 3 (as shown in Figs. 3 and 4 of the drawings).

105 The well or casing 3 having thus been opened the buoy 14 is liberated and will rise to the surface of the water and float thereon above the vicinity of the sunken submarine boat 2, thus marking the location of the same, and warning ships at the surface of the plight of the submarine boat. In rising to the surface, the buoy 14 carries upwardly with it the light line 13. This operation is illustrated more particularly in 110 Fig. 3 of the drawings.

115 Any ship 48 at the surface of the water upon discovery of the buoy 14 may sail thereto and take up the buoy 14, and by means of the light line 13 draw up the 120 hawser or cable 12 to which is attached the free end of the tubular-body 8. The hawser or cable 12 may then be connected with the tackle of a derrick 49 of the rescue ship 48, and drawn up to the surface of the water, bringing up therewith the free end of the tubular-body 8 to the surface, the latter paying out of the well or casing 3 in which it is stowed in collapsed condition. The free end 111 of the tubular-body 8 upon emerging 130

from the surface may be opened, and then suitably supported at the side of the rescue ship, as illustrated more particularly by Fig. 4 of the accompanying drawings. The 5 line 10 passing through said tubular-body 8 may thus be connected with a suitably sized cable or hawser 44, and the crew of the submarine when signaled may haul down this cable or hawser 44, which can 10 be then attached to the upper head 42, of the carrier or elevator-member 40. The hatch-plate 6 having in the meantime been opened the carrier or elevator member 40 may be inserted therethrough, and the cable or hawser 45 connected with the lower head of the carrier or elevator member 40. A member of the crew of the submarine 15 may now enter the carrier or elevator member, and the same may then be pulled 20 through the interior of said tubular-body 8, which provides an escape passage 50, by means of the derricks of the rescue ship.

If the pressure of the water upon the exterior side of the walls of the tubular-body 25 8 tends to flatten the same together, the conical heads 42 of the carrier or elevator-member, as it pushes against the inner side of the same under the raising force applied thereto, will readily push or spread the 30 walls of the tubular-body 8 apart, so as to render easy and assured the quick upward passage of the carrier or elevator-member 40 with the member of the crew therein, who is also protected against the pressure 35 of the water by the inclosing rigid sides of said carrier or elevator member 40. The said carrier or elevator member 40 may be returned to the submarine boat 2 through the escape passage 50 of the tubular-body 40 8, by pulling downwardly on the cable 45 from within the boat 2, thus returning the carrier or elevator member to the submarine boat so that the next member of the 45 crew may enter therein and be conveyed to the surface of the water, and so the above operations of the escape apparatus may be repeated until all the crew of the submarine boat have been rescued. In returning the carrier or elevator-member to the submarine boat 2 through the tubular-body 8, the lower conical head of the former will 50 readily spread or open the latter to the passage thereof, even against great external water pressure on the exterior side of the tubular-body 8.

From the above description it will be clearly evident that the present invention provides a simple compact, and easily operated rescue or escape apparatus adapted to 55 be carried by the submarine boat itself, and readily released to communication with the surface of the water, so as to be accessible to, and afford means to a rescue ship for communication with and the rescue of the 60 imprisoned crew of the submarine boat.

The carrier or elevator member may be carried by the submarine boat, and it may also be supplied to rescue ships as an extra equipment.

Of course, the various forms of construction of the different parts of my novel escape apparatus for submarine boats may be widely varied, as well as the combinations and arrangements of such parts, hence I intend to claim the apparatus generically, 70 and do not limit myself to the precise construction of the details thereof, nor the precise arrangement and combination of the parts thereof. I therefore do not limit my invention to the exact arrangements and 75 combinations of the various parts or to the exact details of said parts as described in the foregoing specification, nor do I limit the invention to the exact details of the construction of said parts as illustrated in the 80 accompanying drawings.

I claim:—

1. An escape apparatus for submarine boats comprising a well connected with the 90 deck of said submarine boat, a hatch connected with the bottom of said well and communicating with the interior of said boat, a hatch-plate for normally closing said hatch, a collapsible tubular-body providing an escape-passage secured by its lower end 95 to said hatch and in communication therewith, said tubular-body when collapsed being stowed in said well, a buoy normally confined in said well, flexible connecting means securing said buoy with the free end 100 of said tubular-body, a line passing longitudinally through said tubular-body, a cover-member for normally closing said well, and means for removing said cover-member from closed relation to said well 105 operable from within the interior of said boat.

2. An escape apparatus for submarine boats comprising a hatchway formed in connection with the deck-portion of said 110 boat, a hatch-plate for normally closing said hatch-way, a collapsible tubular-body providing an escape passage secured by its lower end to said hatchway and in communication therewith, a normally closed compartment above said hatchway for stowing said tubular-body when collapsed, a buoy in said compartment, a light line connected with said buoy and stowed in said compartment above said collapsed tubular-body, a heavy cable connected with the free end of said collapsed body and stowed above the same in said compartment, said heavy cable being connected with the opposite end of said light line, a cover-member for normally closing said compartment to normally retain therein said buoy, tubular-body and interconnecting parts, mechanism for removing said cover-member from closing relation to said compartment operable from 115 120 125 130

within the interior of said submarine boat, and an elevator-member adapted to be inserted in and passed back and forth through the escape passage of said tubular-body 5 when the latter is extended for use, said elevator-member comprising a cylindrical shell having an opening giving entrance thereto, a conical head at each end of said shell, and means connected with each head for attaching 10 hauling cables thereto.

3. An escape apparatus for submarine boats, comprising a collapsible tubular-body connected by its lower end with said boat, a line normally extending through and stowed 15 with said tubular-body, a normally closed hatchway between the lower end of said tubular-body and the interior of said boat, hauling lines connected with the free end of said tubular-body whereby the free end of 20 the latter may be hauled upward to the surface of the water and as thus extended provide an escape passage therethrough in communication with the interior of said boat, a buoy connected with said hauling lines for conveying the latter to the surface of the water, a normally closed compartment for stowing said buoy; collapsed tubular-body and interconnecting hauling lines, and a removable cover-member for normally 25 closing said compartment, means operable from within the submarine boat for removing 30 said cover-member to release said buoy and opening said compartment for the withdrawal and extension of said tubular-body 35 therefrom.

4. An escape apparatus for submarine boats comprising a collapsible tubular-body connected by its lower end with said boat, a line normally extending through and 40 stowed with said tubular-body, a normally closed hatchway between the lower end of said tubular-body and the interior of said boat, hauling lines connected with the free end of said tubular-body whereby the free 45 end of the latter may be hauled upward to the surface of the water and as thus extended provide an escape passage therethrough in communication with the interior of said boat, a buoy connected with said hauling 50 lines for conveying the latter to the surface of the water, a normally closed compartment for stowing said buoy, collapsed tubu-

lar-body and interconnecting hauling lines, a removable cover-member for normally closing said compartment, means operable 55 from within the submarine boat for removing said cover-member to release said buoy and opening said compartment for the withdrawal and extension of said tubular-body 60 therefrom, and an elevator-member adapted to be inserted in and passed back and forth through the escape passage of said tubular-body when the latter is extended for use.

5. An escape apparatus for submarine 65 boats comprising a collapsible tubular-body connected by its lower end with said boat, a line normally extending through and stowed with said tubular-body, a normally closed hatchway between the lower end of said 70 tubular-body and the interior of said boat, hauling lines connected with the free end of said tubular-body whereby the free end of the latter may be hauled upward to the surface of the water and as thus extended provide an escape passage therethrough in communication with the interior of said boat, a buoy connected with said hauling lines for conveying the latter to the surface of the water, a normally closed compartment for 75 stowing said buoy, collapsed tubular-body and interconnecting hauling lines, a removable cover-member for normally closing said compartment, means operable from within the submarine boat for removing 80 said cover-member to release said buoy and opening said compartment for the withdrawal and extension of said tubular-body 85 therefrom, and an elevator-member adapted to be inserted in and passed back and forth through the escape passage of said tubular-body when the latter is extended for use, said elevator-member comprising a cylindrical shell having an opening giving entrance thereto, a conical head at each end of said 90 shell, and means connected with each head for attaching hauling cables thereto.

In testimony, that I claim the invention set forth above I have hereunto set my hand this 17th day of April, 1915.

DAVID C. MARSHALL.
